UNITED STATES PATENT OFFICE.

HART A. STODDARD, OF PHILADELPHIA, PENNSYLVANIA, ASSIGNOR TO CHELTEN ELECTRIC COMPANY, A CORPORATION OF PENNSYLVANIA.

PLUG AND RECEPTACLE.

1,246,677.

Specification of Letters Patent. Patented Nov. 13, 1917.

Application filed January 16, 1914. Serial No. 812,557.

To all whom it may concern:

Be it known that I, HART A. STODDARD, a citizen of the United States, and a resident of the city of Philadelphia, county of 5 Philadelphia, and State of Pennsylvania, have invented certain new and useful Improvements in Plugs and Receptacles, and of which the following is a complete description.

10 The object of the invention is to provide a receptacle comprising spaced resilient jaws, and a plug having a member adapted to enter said jaws, said jaws and plug being provided with coöperating means for 15 removably locking the latter in the former.

Another object is to provide such a receptacle having a shoulder raised from the plane of the inner surface of one of said jaws, and a plug member adapted to be inserted 20 between said jaws and having a recess, said shoulder being adapted to engage the walls of said recess to removably lock said member in place.

Another object is to provide a jaw member having a locking device equally applicable to a plug member having a recess in either of its lateral surfaces or on an edge.

A further object is to provide a receptacle 30 contact member comprising a pair of resilient jaws and a binding post or plate integrally connected thereto, though removed therefrom.

A still further object is to provide a novel 35 means for immovably securing the lugs, to which the face plate is connected, to the insulating receptacle block or base.

And another object is to provide a plug contact member having a side provided 40 with a shoulder to frictionally engage a side of a resilient receptacle contact.

Numerous additional objects and advantages of the invention are clearly brought out in the following specification when read 45 in conjunction with the accompanying drawings, in which Figure 1 is a front elevation of the improved receptacle with face plate attached; Fig. 2 is a vertical, longitudinal sectional view of the same; Fig. 3 is a side 50 elevation of the improved plug; Fig. 3^a is a bottom plan view of the same; Fig. 4 is a top plan view of the same; Fig. 4^a is a perspective view of a combined receptacle contact member and binding post; Fig. 5 55 is a rear elevation of the receptacle; Fig. 6

is a detailed view of the coöperation of the respective plug and receptacle contact members; Fig. 7 is a section of the same as indicated on Fig. 6; Fig. 8 is a plan view of one form of plate-attaching lug and its means of support; Fig. 9 is a section on the line 9—9 of Fig. 8; Fig. 10 is a plan view of another form of lug and its support; Fig. 11 is a section on the line 11—11 of Fig. 10; Fig. 12 is a plan view of a third form of lug and its support; Fig. 13 is a section on the line 13—13 of Fig. 12; Fig. 14 is a fragmentary view showing the coöperation of the receptacle contact locking means coöperating with the locking means of a modified form of plug contact; and Fig. 15 is a view of the member shown in Fig. 4^a secured in position on the receptacle base block.

Referring to the drawings, the invention 75 in its preferred form comprises a base block 20 provided with a central raised or projecting portion 21 adapted to be inserted through the hole 22 in the face plate 23, and have its face flush with or extending beyond the outer side thereof. Said block is provided with two similar apertures 24, extending therethrough and enlarged to form 80 an L-shaped recess 25, while within said aperture and recess is secured a metallic 85 contact member 26, L-shaped, as shown in Fig. 5 and provided upon one end with integral, parallel, resilient, U-shaped jaws 27 beveled at their outer ends 28 and terminating 90 a relatively short distance from or flush with the face of said projection 21, said member being secured in place by a screw 29. From the other end of said member a screw 30 passes through the block and secures in place a post or plate 31, as well as 95 forming an electrical connection therebetween, said plate in turn being provided with a binding screw 32 for securing there-to an electrical conductor.

To the forward part of the said base 100 block, are secured in any suitable manner lugs 35, as by the screws 36, to which is secured the face plate 23 by screws 37, each of said lugs having a bearing portion 38 against which said plate is firmly drawn by 105 said screws to hold said plate rigidly, the bearing portions coöperating with said plate in recesses 39, and said lug having the usual apertures 40 for well-known purposes.

For securing the lugs 35 to the base 110

blocks a novel method is shown in each of the groups of Figs. 8 and 9, 10 and 11, and 12 and 13 in each case the result being that upon tightening the screw 45, the lug is secured firmly in such manner as to prevent a rotation or oscillation upon the end of the screw, as often occurs in such cases where a flat lug is secured against a flat surface.

- The form shown in Figs. 8, and 9 provides 10 a lug having a central depressed portion 46, the sides 47 of which are beveled to coöperate, as the sides of a wedge, with the beveled sides 48 of a recess 49 in the base block 20. The form shown in Figs. 10 and 11 on the 15 other hand provides a lug having a central raised or embossed portion 50, the sides 51 of which are beveled to coöperate with the sides 52 of a raised portion 53 on said base block. In Figs. 12 and 13 the lug is provided 20 with a downwardly turned flange 55 at right angles to the line of symmetry of said lug and coöoperating with a beveled surface 56 on the base block. In any of these constructions, it is therefore obvious that a 25 tightening of the screw 45 causes said lug to become wedged into a final position from which it cannot move in its own plane, or any other, except by first loosening said screw.
- 30 The plug which it is preferred to use in conjunction with the hereinbefore described receptacle is shown in Figs. 3, 3^a and 4 and comprises a substantially circular block 60 provided with a central hole 61 opening at 35 its inner end into an enlarged recess 62, adapted to contain the knotted portion of one or more wires passing therethrough, and thence into a still larger recess 63, against the plane surface of which are secured contact members 64 by screws 65 or other suitable means, the inner end of said members being provided with binding screws 66 and up-turned lugs or shoulders 67, to aid in firmly securing a wire connection thereto. 40 The outer ends of said contact members are preferably turned, or curved slightly, so as to form a shoulder 68 as shown in Fig. 7, while farther up the shank thereof holes 69, counter-sunk from each side, are provided. 45 Correspondingly, one of each pair of resilient jaws 27 is indented from the outside, or otherwise mutilated, to provide a shoulder or lug 70 upon the inner side thereof for coöperating with the walls of the counter- 50 sunk recesses 69 on the plug blades, to lock the latter temporarily in position when desired. Furthermore, said shoulders 70 are purposely positioned adjacent to one side of said jaw members, to equally well lock in 55 position a plug blade provided with a lateral notch 71, as shown in Fig. 14, the coöperation and locking of the plug and receptacle contacts being shown in Figs. 6 and 7.

A modified form of combined receptacle 60 contact member and binding plate or post

is shown in Figs. 4^a and 15 and comprises an L-shaped member 75, provided on one end with parallel resilient jaws 76, and upon the other end with a vertical extension 77, bent horizontally and provided with a tapped 70 hole 78 for a binding screw, and with the well-known lug 79, at its angle, said member having a tapped hole 80, for securing the former in place by the ordinary screw 29. In this form it is necessary in assembling 75 the receptacles to insert the extension 77 through a hole in the base block and then bend the end over. However, a more efficient way lies in providing the block 20 at diagonally opposite corners with a substantially rectangular recess 82, as shown in Fig. 15, in which case the member 75 is bent into its final shape and then secured in position upon the block 20 by the usual screw 29.

This construction in either its preferred 85 or modified forms permits of a more shallow base block than is usually found on the market, while the projection 21 makes a neat, and substantially flush finish of said block with the surrounding portion of the 90 face plate. And, by terminating the contacts below the surface, all danger of accidentally bridging them by a foreign object is obviated. Furthermore, many changes 95 from the exact details shown and described can be made without departing from the spirit of the invention or the scope of the appended claims.

I claim and desire to protect by Letters Patent of the United States:

1. The combination of a one-piece receptacle base block, provided with an aperture opening toward the front thereof, a second aperture also opening toward the front thereof, and spaced from the first, and a 105 groove or channel in the rear exposed surface of said block connecting said apertures, with an integral electric conducting member struck from a single blank comprising a contact portion located in said first aperture, 110 a portion provided with means for securing an electrical conductor thereto located in said second aperture, and a portion integrally connecting said other portions and lying in said channel or groove. 115

2. The combination of a one-piece receptacle base block, provided with an aperture extending through and opening toward the front thereof, a second aperture also extending through and opening toward the front 120 thereof and spaced from the first, and a groove or channel in the rear outermost portion of said block connecting said apertures, with an electric conducting member formed from a single blank and comprising a pair 125 of integral contact portions located in and extending to a point adjacent to the front of said first aperture, a portion provided with means for securing an electrical conductor thereto located in and extending to 130

a point adjacent to the front of said second aperture, and a portion integrally connecting said other portions and lying within said channel or groove.

5 3. The combination of a receptacle base block, having a portion of its surface lying to one side of the plane of the rest of said surface and having beveled side walls, and a plate-securing lug having a transversely 10 central section of substantially the same shape and extent as said portion and having beveled side walls, and means to secure said block and lug together with the respective side walls of said portion and section in 15 binding coöperation, to prevent oscillation of said lug upon said block.

4. The combination of a receptacle comprising a pair of oppositely disposed substantially parallel resilient contact members, 20 one of which is provided with a projection adjacent to one side, and a plug comprising a contact member, engageable between said first mentioned contact members and provided with a counter-sunk recess adjacent to 25 one side of said last-named member, said projection coöperating with the walls of said recess, to removably lock said plug in said receptacle, said plug contact member terminating in a shoulder adapted to frictionally 30 engage one of said resilient contact members.

5. The combination of a receptacle comprising a pair of oppositely disposed substantially parallel resilient contact members, 35 one of which is provided with a projection adjacent to one side, and a plug comprising a contact member, engageable between said first mentioned contact members and provided with a counter-sunk recess adjacent to 40 one side of said last-named member, said projection coöperating with the walls of said recess, to removably lock said plug in said receptacle, said plug contact member terminating in a shoulder adapted to frictionally 45 engage one of said resilient contact members, and located on the side of said plug contact opposite to said receptacle projection.

6. The combination of a receptacle comprising a pair of oppositely disposed substantially parallel resilient contact members, 50 one of which is provided with an offset, and a plug comprising a contact member, engageable between said first mentioned contact members and laterally directed at its end to provide an offset or shoulder, operative to frictionally engage the other of said receptacle contact members, to removably lock said plug to said receptacle. 55

7. A receptacle base block comprising a portion thereof provided with oppositely slanting sides, a lug provided with oppositely slanting surfaces operative to engage said sides, and means to secure said lug in binding relation to said portion to prevent a transverse movement of said lug with respect to said portion. 60 65

8. A receptacle base block comprising a portion thereof provided with oppositely slanting sides, an attaching lug provided with oppositely slanting surfaces operative to engage said sides, and means for securing said lug to said portion with a variable binding tension, to compensate for inaccuracies in either to prevent a transverse movement of one with respect to the other. 70 75

9. A receptacle base block comprising an integral portion thereof provided with diverging sides having a substantially equal degree of slant, an attaching lug provided with diverging surfaces operative to engage 80 said sides in wedged, binding relation, and means for securing said lug to said portion and against said surfaces with a variable tension, to compensate for inaccuracies in either, and operative to insure a substantially uniform engagement of said surfaces with said sides. 85

In witness whereof, I have hereunto set my hand this 14th day of January, A. D., 1914.

HART A. STODDARD.
